[57] **CLAIM**

The ornamental design for perforated hose for injection
filling of sealing material in casting joints, as shown and
described.

DESCRIPTION

FIG. 1 is a perspective view of a perforated hose for
injection filling of sealing material in casting joints
showing my new design;

FIG. 2 is an end elevational view thereof, the opposite
end being the same as the end shown;

FIG. 3 is a cross-sectional view taken on line III—III of
FIG. 1;

FIG. 4 is a fragmentary cross-sectional view taken on
line IV—IV of FIG. 2; and,

FIG. 5 is another perspective view thereof showing one
end broken away for convenience of illustration.
It is to be understood that the center of the hose is
broken away in FIG. 1 to indicate indeterminate length
and that the braided net covers the hose from end to
end, but is broken away in FIGS. 1 and 5 for purposes
of illustration.
